UNITED STATES PATENT OFFICE.

PHILLIP A. SCHMUCK, OF LOS ANGELES, CALIFORNIA.

BULL-ROPE PROTECTOR.

1,074,212.

Specification of Letters Patent. Patented Sept. 30, 1913.

Application filed February 1, 1912. Serial No. 674,694.

To all whom it may concern:

Be it known that I, PHILLIP A. SCHMUCK, a citizen of the United States, residing at Los Angeles, in the county of Los Angeles 5 and State of California, have invented new and useful Improvements in Bull-Rope Protectors, of which the following is a specification.

This invention relates to improvements in 10 bull rope protectors and shifters and it is an object of the invention to provide a mechanism by which the usual bull rope of a well boring mechanism, may be lifted or shifted and held out of engagement with the tug 15 wheel which is employed to drive it in operating the bull wheel.

It is also an object of the invention to provide a lever mechanism adapted to raise 20 and hold the bull rope of a well operating mechanism, out of engagement with the revolving tug wheel when it is not desired to operate the bull wheel.

In the accompanying drawing forming a part of this specification, Figure 1 is a side 25 elevation of a tug wheel, and a portion of a bull wheel being also shown in side elevation and as lifted from the tug wheel by the improved mechanism forming the subject matter of this invention. Fig. 2 is an 30 edge elevation of the tug wheel and adjacent band wheel driven by the engine of the mechanism not shown, the bull rope protector being shown in position. Fig. 3 is a top plan view of the said band wheel, tug 35 wheel and bull rope protector. Fig. 4 is a detail view in end elevation of the bull rope protector showing two arms employed for lifting the bull rope. Fig. 5 is a detail view in side elevation of the modified form 40 of bull rope protector shown in Fig. 4 and showing also a rope for lifting the same.

The details and features of the invention will now be more particularly described, reference being had to the said drawing in 45 which—

5 indicates a bull rope of the ordinary type employed in connection with the oil well drilling mechanism. 6 indicates a bull wheel adapted to be driven by the said bull 50 rope, 7 a tug wheel or pulley carried by an adjacent band wheel 8 which is driven by a belt 9 extending to an engine not shown. The tug and band wheels 7 and 8 are mounted upon a shaft 10 which is journaled 55 upon suitable pillars 11 in the usual manner. The band wheel 8 is ordinarily driven more

or less continuously by the engine and when the bull rope 5 is not being employed for driving the bull wheel it is either necessary to allow it to rub loosely upon the said tug 60 wheel, or to have an attendant go around into the engine housing and close to the rapidly moving band wheel and tug wheel and lift the bull rope off. The present invention obviates this loss of time and danger and affords means for shifting the bull 65 rope from a position outside the usual housing built around the engine and the band wheel. In operating the bull wheel 6 also it now usually requires the shutting 70 down of the engine temporarily to place the bull rope upon the bull wheel and upon the revolving tug wheel 7.

The improved mechanism forming the subject matter of this invention is adapted 75 to suspend and hold the bull rope out of contact with the tug wheel when the bull wheel 6 is not being operated and to facilitate the dropping of the bull rope upon the said tug wheel when the bull wheel is to be 80 driven, an operator being able to accomplish the whole operation from a position near the well tools, outside the engine house, and without stopping the engine. The mechanism for effecting this purpose comprises 85 a pivoted bar 12 which is journaled at its lower end upon a bolt 13 secured to one of the pillars 11. The upper end of said bar 12 extends slightly above the tug wheel 7 and is provided with an arm 14, which is 90 journaled upon the said bar 12 and supported thereon at a proper height by means of an adjustable collar 15. A set screw 16 affords means for holding the said collar 95 adjustably in place. The bar 14 is formed with an enlargement or eye 17 which fits rather snugly upon the bar 12 so as not to swing out of position ordinarily. Its engagement with the bar, however, is such 100 that it can be forced to one side by the action of the bull rope when necessary. Ordinarily the said arm 14, however, extends inwardly toward the band wheel, over the periphery of the tug wheel as shown in Figs. 2 and 3.

A thrust rod 18 is pivoted at 19 to the bar 12 and its outer free end extends outside the engine house (not shown) and is provided with a hand hold 20. By pulling upon the hand hold 20 when the parts are in the position shown in Fig. 1 and the arm 14 is 110 holding the bull rope out of engagement

with the tug wheel, the arm 12 may be rocked forwardly to the position shown in dotted lines in said Fig. 1 so as to drop the bull rope upon the tug wheel. At this time the 5 bull rope is also put upon the periphery of the bull wheel 6 so that the said rope will communicate movement from the tug wheel, to the bull wheel and will not engage the lifting mechanism. The said lifting and 10 protecting mechanism when thus lowered may rest upon a transversely arranged supporting bar 21, secured to the adjacent framing of the wheel mechanism.

When it is desired to discontinue the use 15 of the bull wheel the bull rope 5 is drawn from its periphery, without stopping the band wheel 8 or the tug pulley or wheel carried thereby. Then the arm 12 is formed to 20 its upright position as shown in full lines in Fig. 1 so as to lift the said bull rope out of engagement with the periphery of the tug wheel or pulley. In this position the band wheel 8 with the tug wheel or pulley 7, can 25 continue its operation under the action of the belt 9 and yet will not wear upon or engage the bull rope. Sometimes it is desired 30 to start the bull rope in the opposite direction from that heretofore described, especially when the engine is reversed, and the movement of the band wheel 8 is in an opposite direction. In such event the bull rope 35 5 is pulled upon so as to draw it against the bottom of the tug wheel or pulley 7 and since the bar 12 cannot move outwardly, because of the shaft 10, the arm 14 will be turned to one side by the bull rope, so as to be thrown out from beneath it and the bull rope will then drop into place upon the groove of the pulley or wheel 7. It will 40 thus be apparent that the device is useful for holding the bull rope and for permitting of its being put in place again whenever it is necessary to drive the bull wheel.

As shown in Fig. 4 the construction of 45 the bull rope lifting mechanism may be slightly modified and the outer end of the bar 12 may be provided with a cross bar 22, the ends of which are provided with upturned standards or end portions 23 upon 50 which arms 24 are pivotally mounted, the said arms being practically the same as the arm 14 heretofore described. By this construction the bar 12 may be made to support

the bull rope at two points instead of at one for further insuring the complete disengagement of the said bull rope from the tug wheel. In this instance also as shown in Fig. 5 a lifting rope 25 may be employed and connected with an eye 26 in the upper end of the bar 12 for lifting it instead of 55 using the thrust rod 18 heretofore described, the said rope extending to any desired point outside the engine house. The action of the parts is practically the same as already set forth and needs no further description. 60 65

What I claim is:

1. In a bull rope protector, the combination with a tug wheel and its support, of a bar pivotally mounted on said support and movable in a plane parallel with the periphery of the tug wheel limited by its contact with the shaft of said tug wheel, a stop adjacent said bar to support said bar, and a contact arm slidably mounted on said bar, extending over the groove in said tug wheel, 70 an adjustable sleeve to adjust and support said contact arm, and an operating rod secured intermediate said pivotal mounting and said contact arm on said arm provided with a handle to swing said bar, whereby 75 the bull rope is lifted and held out of contact with said tug wheel by said bar engaging said shaft, and also supported on said stop.

2. In a bull rope protector, the combination with a tug wheel and its support, of a bar pivotally mounted on said support and movable in a plane parallel with the periphery of the tug wheel limited by its contact with the shaft of said tug wheel, a stop adjacent said bar to support said bar, and a contact arm slidably mounted on said bar, extending over the groove in said tug wheel, 80 an adjustable sleeve to adjust and support said contact arm, and means to swing said bar, whereby the bull rope is lifted and held 85 out of contact with said tug wheel by said bar engaging said shaft, and also supported on said stop.

In witness that I claim the foregoing I 100 have hereunto subscribed my name this 20th day of January 1912.

P. A. SCHMUCK.
